(57) **CLAIM**

The ornamental design for a payment terminal, as shown and described.

DESCRIPTION

FIG. 1 is a front, left side, and top perspective view of a payment terminal showing the new design;

FIG. 2 is front elevation view thereof;

FIG. 3 is a rear elevation view thereof;

FIG. 4 is a left side elevation view thereof;

FIG. 5 is a right side elevation view thereof; and,

FIG. 6 is a top plan view thereof.

The features in broken lines are included for the purpose of showing portions of the payment terminal that form no part of the claimed design.
